(57) CLAIM

The ornamental design for a toilet brush and housing assembly, as shown and described.

DESCRIPTION

FIG. 1 is a front perspective view of the toilet brush and housing assembly showing the new design;

FIG. 2 is a front view thereof;

FIG. 3 is a rear view thereof;

FIG. 4 is a right side view thereof (the left side view is a mirror image thereof);

FIG. 5 is a top plan view thereof;

FIG. 6 is a bottom plan view thereof; and,

FIG. 7 is a front perspective view of the toilet brush, with the housing depicted in broken lines so as not to obscure the portion of the toilet brush supported therein.
